CLAIM

The ornamental design for a produce box, as shown and described.

DESCRIPTION

FIG. 1 is a front perspective view of a produce box, showing the new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a front perspective view thereof.

The broken lines in the figures illustrate unclaimed portions of the produce box.

1 Claim, 8 Drawing Sheets
